OF IOWA.

BROOM-CLAMPING MACHINE.

1,257,138.

Specification of Letters Patent. Patented Feb. 19, 1918.

Application filed November 15, 1916. Serial No. 131,451.

To all whom it may concern:

Be it known that we, HARRY E. SMITH and GEORGE W. DUVALL, citizens of the United States, residing at Davenport, in 5 the county of Scott and State of Iowa, have invented certain new and useful Improvements in Broom-Clamping Machines, of which the following is a specification.

Our invention relates to an improvement 10 in broom-clamping machines, and more particularly to that class of machines used to fasten the clamps or jaws of metal clamp brooms.

This invention is an improvement on a 15 co-pending application of Norman H. Beebe, on broom clamping machines, Serial No. 10,758, and pertains particularly to a releasing mechanism for the upper clamp, which will be more fully disclosed and de- 20 scribed in the following description.

In the accompanying drawings:—

Figure 1 is a front elevation of the clamping portion of the machine, showing the various parts in the position they occupy 25 when ready to begin the clamping operation;

Fig. 2 is a side elevation of Fig. 1;

Fig. 3 is a similar view showing the upper cross-head lowered and in the act of 30 compressing the fiber, at which time the upper clamp releasing mechanism has released the clamp; and

Fig. 4 is a detail perspective view of the clamp-release mechanism.

Fig. 5 is a detail perspective view of the 35 bell crank and finger.

The numeral 1 indicates the main frame. Numbers 2 and 3 indicate the upper and lower movable cross-heads slidably held by 40 suitable guides to the main frame. A clamp form 4 is attached to the lower end of the upper cross-head. A similar clamp form 5 is attached to the lower pressure-head 6, which is adjustably secured to the main 45 frame 1.

7 is an anvil attached to the form 5. Co-operating with this anvil is a plunger 8, which is slidably held in the upper cross-head 2. The upper and lower cross-heads 50 2 and 3, together with the plunger 8, are all suitably actuated by cam-members, all of which operation is clearly described in the above-mentioned co-pending application.

Oscillating fingers 9 and 10 are pivoted

to the main frame and are open at their 55 lower ends thereby forming a housing for the bell cranks 11 and 12 received within and pivoted thereto, as shown in Fig. 5. Plungers 14 and 15 are attached to the lower sliding head 3 and are adapted to come in 60 contact with the fingers 9 and 10 and force them to a comparatively vertical position upon the upward movement of the plunger. Additional abutments 16 and 17 are arranged on the lower cross-head and are adapted to 65 engage the bell-cranks 11 and 12. These abutments come in contact with the bell-cranks during the clenching operation.

For the purpose of forming the staple 18, as shown in Fig. 1, into a ring, the plunger 70 8 is employed, which operation is clearly described in the above-mentioned co-pending application.

Numerals 19 and 20 are the broom-clamps, which are provided with hooked ends 21, 21 75 and 22, 22 respectively. The clamp 20 is adapted to rest upon the lower clamp-form 5, while the clamp 19 is adapted to be held or retained in the upper clamp-form, preferably in the following manner:— 80

The clamp-form 4 is provided at its rear with pins 4', 4', which pins slightly hook over the ends of the clamp. Pivotaly mounted upon the face of the cross-head 2 is a clamp-holding-finger 23, which is piv- 85 otally mounted upon the cross-head to a member 24, forming a hinged joint therefor. As will be noted in Fig. 2, the lower end of this holding-finger is adapted to clench the front edge of the clamp-form 19. A 90 reach rod 25 is movably attached to the clamp-holding-finger. This rod 25 is pref- erably screw-threaded at its upper end, and is adapted to receive a plate 26, being secured thereto by the lock-nut 27. 95 Attached to the plate 26 is the yoke 28. This yoke is provided with a slot 29, and passing loosely therethrough is a bolt 30. This bolt is screwed into the center of the broom-machine shaft, and a collar or spacer 100 31 serves to maintain the rod in a practically vertical position. Interposed between a col- ller 32 upon the rod 25, and a post 33 se- cured to the cross-head and surrounding the rod is a compression spring 34, which, as 105 will be seen, tends to force the rod down- wardly, thereby increasing the gripping properties of the holding-finger 23.

The operation of the machine is as follows:—The staple is first placed in a semi-annular groove in the anvil 7, with its two ends extending upwardly. The clamp 20 is now placed in the lower form 5. The clamp 19 is then placed in the upper form 4 and is held therein by means of the holding-finger 23 and the pins 4'. The operator places a quantity of fiber over the lower clamp, as shown in Fig. 1. A handle 35 is inserted between the fibers, with the annular groove 36 of the handle in line with the annular bead 37 of the clamps. The head 3 moves upward, just far enough to cause the plungers 14 and 15 to raise the fingers to a vertical position. The head 3 now remains stationary, and the upper head 2 descends from the position shown in Fig. 1 to that shown in Fig. 3. In this position the hooked ends 21, 21, and 22, 22 of the clamps just pass each other. As the head descends, it carries the entire upper clamp release mechanism, except the bolt 31 secured to the cam-shaft. When the upper clamp 19 comes in contact with the corn fiber 13, the device is so adjusted that the stationary bolt 31 strikes the upper end of the slot in the yoke 28. Therefore, as the head and attached parts continue to move downward, the finger 23 is drawn to a position (as shown in Fig. 3) which will release the upper clamp 19. The upper head 2 now remains stationary, and the lower head 3 moves upward. The abutments 16 and 17 come into contact with the bell-cranks 11 and 12, imparting motion to them.

These bell-cranks in turn force the clamp ends to a straight line, thereby causing the hook members 21, 21, and 22, 22, to come into alinement. During the time of the latter operation, the plunger 8 has descended, curving the staple into the form of a ring in the beads of the clamp. Just as the hook ends of the clamp are brought into a straight line, the head 2 rises. The pressure of the fiber forces the clamps apart, thus causing the hooked ends 21, 21 and 22, 22, to hook into each other.

50. The lower head now descends, and the machine is ready to repeat its cycle of operation.

We claim:

1. A broom clamping machine comprising two movable cross-heads, a clamp-form carried by one of said cross-heads, a clamp-form cooperating therewith, said clamp-forms adapted to receive clamps, fingers pivoted to and carried by the frame, bell-cranks carried by said fingers, means carried by the other cross-head in position to engage the bell-crank to cause the latter to exert lateral pressure upon the clamp ends to force them into position to hook or interlock with

each other, and means for automatically releasing the upper clamp from the upper clamp-form. 65

2. A broom clamping machine comprising two clamp-forms, one of which is movable, said clamp-forms adapted to receive clamps, means movable with the form for holding the clamp thereto, means for forcing said clamps together, and means actuated by the movement of the clamp form for automatically releasing said clamp holding means. 75

3. A broom clamping machine comprising upper and lower movable cross-heads, a clamp form carried by one of said cross-heads, a clamp-form cooperating therewith, said forms adapted to receive clamps, a pivoted hook carried by the upper cross-head which is adapted to hold the clamp thereto, means for forcing said clamp-forms together, and means carried by the cross-head adapted to actuate the pivoted hook for releasing said clamps. 85

4. A broom clamping machine comprising upper and lower cross-heads, a clamp-form carried by one of said cross-heads, a clamp-form cooperating therewith, said forms adapted to receive clamps, a pivoted hook carried by the upper cross-head which is adapted to hold the clamp thereto, means for forcing said clamp-forms together, means comprising a vertical rod, the lower end of which is pivoted to said pivoted hook and having its upper end adjustably guided, a guide interposed on said cross-head, and surrounding said pivoted rod, a collar adjustably secured to said rod, a spring interposed between said collar and guide for exerting downward tension on said rod, and means for limiting the downward movement of said rod for actuating the said hook and releasing the said clamp prior to the forcing together of the said clamp-members. 95

5. A broom clamping machine, comprising two movable cross heads, a clamp form carried by one of said cross heads, a clamp form cooperating therewith, said clamp form adapted to receive clamps, said clamps having hooked ends, fingers, and bell cranks pivoted to and carried by the frame, said

fingers and bell cranks pivoted on a common center, one astride the other to house it, and means carried by the other cross head in position to engage the bell cranks to cause the latter to exert lateral pressure upon the clamp ends to force them into position to hook or interlock with each other. 115

6. A broom clamping machine, comprising two movable cross heads, a clamp form carried by one of said cross heads, a clamp frame cooperating therewith, said clamp form adapted to receive clamps, said clamps having hooked ends, fingers, and bell cranks pivoted to and carried by the frame, said fingers and bell cranks pivoted on a common 125

center, one astride the other to house it, means carried by the other cross head to engage the fingers and force them into a vertical position, and additional means carried by 5 the same cross head in position to engage the bell cranks to cause the latter to exert lateral pressure upon the clamp ends to force them

into position to hook or inter-lock with each other.

In testimony whereof we affix our signatures.

HARRY E. SMITH.
GEORGE W. DUVALL.
